(57) **CLAIM**

The ornamental design for the hydraulic gutter cleaning tool, as described and shown.

DESCRIPTION

FIG. 1 is a front side elevation of the hydraulic gutter cleaning tool

FIG. 2 is a rear side elevation of the hydraulic gutter cleaning tool

FIG. 3 is a left side elevation of the hydraulic gutter cleaning tool

FIG. 4 is a right side elevation of the hydraulic gutter cleaning tool

FIG. 5 is a top plan view of the hydraulic gutter cleaning tool; and,

FIG. 6 is a bottom plan view of the hydraulic gutter cleaning tool.

Broken lines are included for the purpose of illustrating portions of the hydraulic gutter cleaning tool and form no part of the claimed design.

1 Claim, 6 Drawing Sheets

FIG. 1

FIG. 2

FIG. 3

FIG. 4

FIG. 5

FIG. 6
